[57] CLAIM

The ornamental design for an embossing device, substantially as shown and described.

DESCRIPTION

FIG. 1 is a perspective view of an embossing device showing my new design and depicted in a closed position;

FIG. 2 is a front elevational view thereof;

FIG. 3 is a right side elevational view thereof;

FIG. 4 is a left side elevational view thereof;

FIG. 5 is a rear elevational view thereof;

FIG. 6 is a top plan view thereof;

FIG. 7 is a bottom plan view thereof;

FIG. 8 is an enlarged, sectional view taken generally along the line of FIG. 1.

FIG. 9 is a perspective view of the device in open position.

*Fig. 1**Fig. 2**Fig. 3**Fig. 4**Fig. 5**Fig. 6**Fig. 7**Fig. 8**Fig. 9*
